J. C. L. CLAYTON

BOX LID HOLDER AND ADVERTISING DEVICE

Filed Aug. 3, 1926

Inventor
J. C. L. Clayton

By Lacy & Lacy, Attorney.

UNITED STATES PATENT OFFICE.

JOHN C. L. CLAYTON, OF GALVESTON, TEXAS.

BOX-LID HOLDER AND ADVERTISING DEVICE.

Application filed August 3, 1926. Serial No. 126,888.

This invention is a device for holding the lid of a cigar box or similar merchandise container in open position flat against the back of the box so that it may be utilized as a support for maintaining the box in an inclined position upon a counter or a show case. The invention also provides means for displaying, in connection with the box, an advertising card identifying the goods and stating the price of the same or giving other information, in the discretion of the store-keeper. The invention seeks to provide a simple and inexpensive device which may be readily applied to a container and furnish means whereby the container may be taken from or restored to a show case to supply a customer and maintain the goods in a sanitary condition. The invention is illustrated in the accompanying drawing and will be hereinafter fully set forth.

In the drawing:

Figure 1 is a perspective view of a container having my improved device applied thereto and arranged to facilitate removal of the container;

Fig. 2 is a transverse section of the device as shown in Fig. 1 and illustrating by dotted lines a different position of the card holder;

Fig. 3 is a detail perspective view.

In the drawing, the reference numeral 1 indicates a cigar box or like container having a lid 2 which is hingedly attached to the back wall of the container at the upper edge of the same so that it may be folded back flat against the back wall and extend below the bottom of the container to permit the container to be supported in an inclined position by being rested upon the free edge of the lid and the lower front corner of the box, as shown in Fig. 1. My lid holder comprises a clip 3 having a back plate 4 which is adapted to rest flat against the lid and is provided at its lower edge with perforated ears 5, said ears being preferably slightly offset, as shown in Figs. 1 and 2, whereby they will project somewhat from the lid. Extending from the upper edge of the back plate is a bridge piece 6 of proper dimensions to extend across the upper edge of the lid and the upper edge of the back wall of the box, as shown in Fig. 2, and depending from the front edge of this bridging plate are teeth or spurs 7 adapted to extend downwardly within the box a short distance and embed themselves somewhat in the back wall, as clearly shown in Fig. 2. This clip will

be formed of spring metal so that it may be easily slipped over the edges of the lid and the wall of the box and bring the teeth into engagement with the box wall so that accidental release of the clip is not apt to occur. Attached to the perforated ears 5 are the upper ends of coiled springs 8 which extend downwardly therefrom over the lid and have their lower ends engaged in similar perforated ears 9 at the upper end of an anchoring member 10. This anchoring member consists of a plate of spring metal doubled upon itself, as shown at 11, whereby it may be engaged over the free edge of the lid, and terminating in a ring or sleeve 12. The bend or bight 11 of this anchoring member may, if desired, be covered with felt, rubber or other material which will prevent slipping of the device upon a glass shelf or the glass top of a show case and also prevent scratching or other marring of a polished surface.

In applying the device, the clip 3 is engaged over the upper edges of the lid and the box wall, as described and shown, and sufficient tension is then exerted upon the springs 8 to permit the ring or sleeve 12 to clear the lower edge of the lid, whereupon, if the pull upon the springs be released, the springs will at once contract and draw the anchoring member into engagement with the lid, as shown in Figs. 1 and 2, so that the device will be securely held in place. In thus applying the device, the finger of the operator may be engaged in the sleeve or ring 12 to be protected thereby. Of course, if preferred, the anchoring plate may be first engaged with the free edge of the lid and the clip then drawn into position.

At the junction of the back plate 4 and the bridging member 6, upstanding lugs 13 are formed thereon and through the said lugs is inserted a pintle or pivot pin 14. Mating with the lugs 13 and mounted on the pintle or pivot pin are similar lugs 15 formed on the side edges of the base portion 16 of a lifter and card holder. The said base portion 16 has one end projected angularly beyond the lugs 15 to form a lip 17 disposed so that, in the position illustrated in full lines upon the drawing, it will bear against the back plate 4 and constitute a stop to dispose the lifter in a position extending upwardly and rearwardly from the container and support the weight of the container when the latter is being removed.

from or placed in a show case. Extending upwardly and rearwardly from the base member 16 is the handle or lever portion 18 of the lifter which may be given any desired contour and may be a continuous solid plate, but will preferably be of the open loop formation shown in the drawing having its outer edges rolled to provide re-entrant flanges 19 adapted to receive a card 20. The card 20 may, of course, be of any suitable material and will be sprung or pushed into engagement with the flanges 19 so as to be retained thereby; and, to further assist in retaining the card in place, a stop tongue 21 is struck up from the material of the lifter to engage over the lower edge of the card, as clearly shown in Figs. 2 and 3. Any desired inscriptions may be placed upon the card 20, such as the name of the cigar, the price of the same, and the dealer's name or matter descriptive of the qualities of the cigar. When the plate is an integral uninterrupted structure, the advertising matter may be printed or otherwise displayed directly thereon, but I prefer the loop formation with re-entrant flanges inasmuch as this construction permits the cards to be changed at will so that, when all the cigars or other articles have been sold from one container, the device may be removed from the empty container and applied to another filled container. The advertising matter may be displayed upon both faces of the card and when the box is within the show case or is at rest upon the counter or shelf, the lifter may be swung forwardly, as indicated by the dotted lines in Fig. 2, so that it will project over the top of the box or container and, therefore, will offer no obstruction to a view of a second rear container. It will be observed that, when the lifter is swung forward, the front face of the base portion 16 will rest upon the bridging member 6 of the clip and will be supported thereby while the stop lip 17 will extend upwardly and will serve as a lever or trip to be engaged by the fingers of the salesman to swing the lifter to the position illustrated in full lines, enabling the salesman to easily lift and control the box which is to be withdrawn from the show case.

When a box is to be withdrawn from a show case, a slight pressure exerted upon the lip 17 will rock the device to the position shown in Fig. 1 and in full lines in Fig. 2 so that it may be easily grasped by the salesman's hand. When the container is returned to the show case, the device may be easily swung over to the position shown in dotted lines in Fig. 2 in which position it will be out of the way of other containers and will plainly display the advertising matter.

The device is exceedingly simple in construction and may be produced at a low cost so that it may be furnished to retail dealers

at a price which will induce them to purchase quantities so that all the boxes may be supplied with the devices. It will not be necessary for the salesman to handle the cigars or other articles at all nor will his fingers or hands be apt to come in contact with the articles when handling the containers equipped with my devices, so that the merchandise will be maintained in a sanitary condition at all times. The clip firmly holds the lid of the box against the back thereof and the device provides a handle or grip which permits the salesman to move the boxes from and to the show case or display position without any fatiguing strain upon the wrist, fingers or hand.

Having thus described the invention, I claim:

1. A device for the purpose set forth comprising a clip to engage over the top edges of the back wall of a box and a lid folded flat against said wall, an anchoring member engageable over the free edge of the folded lid more remote from the hinged edge, and a yieldable connection between the clip and the anchoring member, said connection extending over the lid and tending constantly to draw the clip and the anchoring member toward each other and maintain the engagement of the same with the lid.

2. A device for the purpose set forth comprising a clip including a back plate adapted to rest against the back of a box lid, a bridging member adapted to extend across the hinged edge of the lid and the back wall of a box to which the lid is attached and wall-engaging spurs depending from the edge of the bridging member to engage the box wall, an anchoring member engageable over the free edge of the lid more remote from the hinged edge thereof, and a yieldable connection between the anchoring member and the back plate of the clip drawing the clip and the anchoring member toward each other to maintain their engagement with the lid.

3. A device for the purpose set forth comprising a clip engageable over the hinged edges of a box wall and a lid to hold the lid flat against the box wall, an anchoring member consisting of a spring plate doubled upon itself to engage over the free edge of the lid more remote from the hinged edge thereof and terminating in a finger receiving element at the front side of the lid, and a yieldable connection between the anchoring member and the clip.

4. A device for the purpose set forth comprising a clip engageable over the connected edges of a box wall and a lid to hold the lid flat against the wall and having offset perforated ears at the lower end of its outer portion, a substantially U-shaped anchoring member engageable over the free edge of the lid and provided with offset perforated ears

at its upper end, and contractile springs having their ends engaged in the respective perforated ears.

5. A device for the purpose set forth comprising a clip engageable over the edge portions of a box wall and a lid folded flat against the same, and a display handle member pivotally mounted upon the clip to extend rearwardly therefrom or forwardly 10 thereover and having a rigid terminal portion adapted in one position of the handle member to form a stop bearing against the clip to resist relative movement of the handle member when lifting the box and in 15 another position of the handle member to extend upwardly from the clip and constitute a finger lever.

6. A device for the purpose set forth comprising a clip engageable over a box wall, 20 and a lid folded flat against the box wall, and a handle member pivotally mounted upon the clip and comprising a plate adapted to extend rearwardly from or forwardly over the clip and a rigid terminal member in angular relation to the plates adapted to bear against the rear side of the clip or to project upwardly therefrom, the plate being constructed to receive and hold an advertising card.

30 7. A device for the purpose set forth comprising a clip engageable over the edges of a box wall and a lid folded flat against the

box wall, and a display handle member consisting of a plate having a base portion pivotally mounted upon the clip and having a 35 rigid terminal portion at and in angular relation to the base portion adapted to in one position rest against the rear of the clip and in another position to extend upwardly therefrom, the main portion of the plate extending rearwardly from the clip parallel to the plane thereof in the first-mentioned position and resting on the top of the clip and extending over the box in the second-mentioned position. 40 45

8. A device for the purpose set forth comprising a clip engageable over adjoining edges of a box wall and a lid folded against said wall, an anchoring member engageable over the free side edge of the lid, an extensible connection between the clip and the anchoring member whereby closing of the lid and release of the clip and anchoring member therefrom will be resisted, a display plate hinged to the clip to extend forwardly over the same or project rearwardly therefrom, and a rigid stop fixed to the plate at the hinged end thereof to extend angularly therefrom and bear upon the back of the clip whereby to prevent relative movement of the plate when lifting the box. 50 55 60

In testimony whereof I affix my signature.

JOHN C. L. CLAYTON. [L. S.]
